UNITED STATES PATENT OFFICE.

MANLEY J. CHAPLIN, OF SEATTLE, WASHINGTON.

AIR-VENT FOR BEER-BARRELS.

SPECIFICATION forming part of Letters Patent No. 783,610, dated February 28, 1905.

Application filed April 22, 1904. Serial No. 204,307.

To all whom it may concern:

Be it known that I, MANLEY J. CHAPLIN, a citizen of the United States, residing at Seattle, in the county of King and State of Washington, have invented certain new and useful Improvements in Air-Vents for Beer-Barrels, of which the following is a specification, reference being had therein to the accompanying drawings.

10 This invention relates to certain new and useful improvements in air-vents for beer-barrels and the like.

It has for its object to provide a simple and inexpensive construction of air-vent which 15 may be quickly and positively connected or detached from the receptacle where employed, and more particularly for use with a bung-socket such as illustrated and specified in Patent No. 729,545, issued June 2, 1903,

20 whereby the beer-tap therein described is made interchangeable with the air-vent of the present invention. It is obvious with the use of the beer-tap described in the said invention that no supplemental means other than there- 25 in described is necessary to admit air into the barrel; but many people prefer to use the ordinary spigot for withdrawing the contents, and in such cases it is necessary that air be supplied to replace the beer as drawn off.

30 This has heretofore been accomplished by air-vent plugs having tapered ends, which are driven into auger-holes made in the heads of barrels, a very unsatisfactory arrangement, for not only is it difficult to make a positive 35 connection therebetween, but the tapering ends of the plugs have a tendency to split the heads from blows delivered upon the plug when securing the same in place, and where the barrel-heads are not destroyed by splitting the holes provided for the plugs are after 40 repeated use so enlarged as to unfit them for continued service. I overcome the aforementioned objectionable features inherent to the aforementioned devices by the novel construction and combination of devices hereinafter 45 explained.

In the accompanying drawings, illustrating an embodiment of my invention, Figure 1 is a central longitudinal section through a bung- 50 socket and a device embodying my invention

connected thereto. Fig. 2 is a similar view of the bung-socket. Fig. 3 is a plan view of Fig. 2. Fig. 4 is a detached elevation of the securing-sleeve shown in Fig. 1.

In the said drawings the numeral 1 designates a bung-socket having an exterior screw-thread 2, whereby it is secured to a barrel. The socket is provided with a cylindrical chamber 3, intermediate an enlarged cavity 4, and a contracted opening or orifice 5 at the inner end of the socket. At the outer end of the cavity 4 is an interiorly-projecting flange 6, through which extend two slots 7 diametrically opposite each other, and the inner faces 8 of each of the parts of the flange thus divided incline inwardly in the same circular direction from the respective slots, as plainly shown in Fig. 2 and similarly to that described in the aforementioned patent.

9 is a sleeve of less diameter than the opening within the socket-flange 6 and is provided with two laterally-projecting studs 10, adapted to be entered through the slots 7, so that when the sleeve is turned through the instrumentality of a handle 11 they engage with the sloping faces of the said flange. Fitted loosely within the said sleeve is a tube 12, carrying externally an elastic annular washer 13, of rubber, preferably, and adapted to be compressed between a shoulder 20 at the inner end of the chamber 3 and the adjacent end 14 of the said sleeve when the latter is forced inwardly by the action of the said studs as they are revolved under the faces 8 of the flange parts, whereby a liquid and air tight packing 85 is attained thereat.

Extending within the outer end of the tube 12 and connected thereto, as by screw-threads 14, is a plug 15, having an axial bore 16, which admits air from the outside to a non-return 90 air-valve attached or provided upon the inner end of the plug. An advantageous and simple construction of the aforesaid valve is a funnel-shaped or taper nozzle 17, with its apex protruding axially inward and provided with a 95 normally closed aperture 18 thereat, so formed as to admit air from the outside only when distended, while it is closed by the elasticity of the material, such as rubber, of which it is formed, supplemented by the surrounding 100

external pressure interiorly of the said tube. Until the contents of the barrel or other receptacle to which my invention is applied is to be withdrawn the orifice 5 would be closed 5 by a cork or stopper 19.

To use the device, the sleeve 9 with the tube 12 and its aforesaid attachments are inserted in the socket and the washer 13 compressed, as before described. The joints being thus 10 packed, the tube would be farther inserted to eject the stopper 19, making the device operative.

Having described my invention, what I claim as new, and desire to secure by Letters 15 Patent, is—

1. The combination, with the socket having an opening extending therethrough which is formed with an intermediate chamber, the tube provided with a non-return valve, an elastic 20 washer external of and carried by the said tube, and a sleeve loosely fitted about the said tube, and means for forcing the said sleeve against the said washer whereby the latter is com-

pressed to form a packing between the said tube and the socket, substantially as set forth. 25

2. The combination with the socket, and the sleeve, of the tube extending axially therethrough, the plug provided with an air-inlet, the taper-shaped apertured elastic nozzle on the inner end of the said plug, and the elastic 30 washer carried on the external peripheral surface of the said tube, substantially as set forth.

3. The combination with a socket, a sleeve fitting in said socket, means for securing the sleeve in position in the socket and the washer located in the socket below the end of said sleeve, of a tube passing loosely through said socket and the said sleeve and embraced by said washer, a plug seated in the end of said tube and a valve on said plug. 35

In testimony whereof I affix my signature in presence of two witnesses.

MANLEY J. CHAPLIN.
